(57) **CLAIM**

The ornamental design for alarm indicating output appliances, as shown and described.

DESCRIPTION

FIG. 1 is a front perspective view of our alarm indicating output appliance;

FIG. 2 is a front elevational view thereof;

FIG. 3 is a bottom view thereof;

FIG. 4 is a top view thereof;

FIG. 5 is a right side elevational view thereof; and,

FIG. 6 is a left side view elevational view thereof.

The bottom views of the above-described embodiments have not been illustrated. They are unadorned and not part of the design.
